MULTILIME COATING AND DRYING MACHINE

Peter M. Murphy, Sterling, Ill., assignor to North-western Steel and Wire Company, Sterling, Ill., a corporation of Illinois

Application October 25, 1940, Serial No. 362,723

5 Claims. (Cl. 205—16)

This invention relates to descaling, cleaning and multi-coating of elongated metal material such as metal rods, metal strips and the like.

More specifically, this invention relates to the multilime coating of elongated metal material to provide a built-up heavy lime coating on the material.

This application is a continuation in part of my copending application entitled: "Descaling, cleaning, and coating machine," Serial No. 346,028, filed July 17, 1940.

In my copending application above referred to, there is described and claimed a descaling, cleaning and coating machine which mechanically flexes elongated metal material such as metal rod to crack off and loosen mill scale thereon. The machine is also equipped with a lime coating device for protecting the descaled rod against oxidation. The lime coating device includes a drum rotatably mounted in a tank containing lime water. The drum receives the rod for a plurality of turns therearound and is positively driven to pull the rod through a sheave-type mechanical descaler. As the drum rotates it carries the rod therearound into and out of the lime bath. When operating at high speeds, however, the coating on the rod does not have sufficient time to completely dry between immersions in the bath.

The present machine now provides for a more thorough drying of the rod between immersions in the lime bath.

Therefore, according to this invention, the lime-coating apparatus is equipped with a drier, preferably in the form of an electrically heated open-ended tube. The rod wrapped around the drum in the lime tank is directed for any desired number of passes through the heated tube. Thus the rod can be multi-coated in one lime bath and dried between coatings so as to build up a thicker or heavier lime coating on the rod.

It is, then, an object of this invention to improve the machine described and claimed in my copending application Serial No. 346,028 for producing a heavier lime coating on elongated metal rods.

Another object of this invention is to provide inexpensive apparatus for descaling, cleaning and multi-coating elongated metal rods, strips and the like.

A further object of this invention is to provide an apparatus which mechanically descales, multi-coats and dries elongated metal materials and delivers the multi-coated materials in an unstressed condition to any metal fabricating apparatus, such as drawing dies and the like.

A further object of this invention is to provide a process of increasing the thickness of the lime coating on a metal rod without necessitating the use of more than one coating bath.

Another object of the invention is to provide a compact, inexpensive descaling, cleaning, coating and drying apparatus for metal rods, strips, and the like material.

5 Other and further objects of the invention will be apparent to those skilled in the art from the following detailed descriptions of the annexed sheets of drawings which disclose preferred forms of apparatus forming part of this invention.

While the invention will be hereinafter described in connection with the descaling, cleaning, coating, drying and drawing of metal rod it should be understood that machines of this 15 invention are adapted for use with any elongated flexible metal material such as wires, strips, ribbons and the like.

On the drawings:

Figure 1 is a side elevational view of a descaling, cleaning, coating and drying machine 20 according to this invention.

Figure 2 is a rear end elevational view of the machine shown in Figure 1 taken along the line II—II of Figure 1.

25 Figure 3 is a top plan view of the machine shown in Figure 1.

Figure 4 is a transverse vertical fragmentary cross-sectional view with parts shown in end elevation of a slightly modified form of apparatus according to this invention.

Figure 5 is a fragmentary plan view, with parts broken away and shown in horizontal cross section, of the machine shown in Figure 4.

Figure 6 is a horizontal cross-sectional view 35 taken through a different type of heater useful on the apparatus of this invention and illustrating the rod passes through the heater.

As shown on the drawings:

In Figures 1 to 3 inclusive the reference character A designates a suitable frame supporting a vertical plate 10 and a horizontal plate 11. An apertured guide block 12 is mounted on the inlet end of the plate 10 and receives a rod R there-through. Guide rollers 13 are rotatably carried 40 on one vertical face of the plate 10 in superimposed relation and receive the rod R therebetween.

Three peripherally grooved sheaves 14 are rotatably mounted in spaced relation on the same 50 face of the plate 10 carrying the guide rolls 13. The rod R passes from the guide rolls 13 over the sheaves 14.

The plate 10 has cut-out portions 10a extending from the top thereof into spaced relation from the bottom as best shown in Figure 1. Additional peripherally grooved sheaves 15 are rotatably mounted on blocks 16 slidably in the cut-out portion 10a. The sheaves 15 are thus positioned between the sheaves 14.

the bottoms of the cut-out portions 10a by means of adjusting bolts 17 which are threaded through bars 18 bridging the open tops of the cut-out portions 10a.

The rod R thus passes over the sheaves 14 and under the sheaves 15 and is flexed or bent in a vertical plane in amounts controlled by the positions of the adjustable sheaves 15.

The rod R, after passing over the last sheave 14 on the plate 10, is next directed over horizontally mounted sheaves 19 rotatably carried on the top face of the horizontal plate 11. The sheaves 19 are in spaced relation and receive an adjustable sheave 20 therebetween. The sheave 20 is carried on a guide block 21 in a cut-out portion 11a of the plate 11. This cut-out block 21 is controlled by a bolt 22 threaded through a bar 23 bridging the open end of the cut-out portion 11a. The sheaves 19 and 20 thus flex the rod R in a horizontal direction, or at right angles to the flexing effected by the sheaves 14 and 15.

The rod R is therefore flexed in a plurality of directions and mill scale formed on the rod by the usual hot rolling operation in the preparation of the rod is loosened and cracked off.

As best shown in Figures 1 and 3, a guide block 24 is mounted on the end of the plate 11 and receives the flexed rod R therethrough from the last sheave 19.

A tank 25 is suspended in a frame B in spaced 30 longitudinal relation from the frame A. The frames A and B can be connected together with a bracket C (Figure 1).

The tank 25 is divided by a partition wall 26 into a compartment 27 in longitudinally aligned 35 relation with the guide block 24 and a compartment 28 in offset relation from the guide block as best shown in Figure 3.

The framework B carries bearing blocks 29 on each side of the tank 25 and a shaft 30 extends across the open top of the tank 25. A drum 31 is secured on the shaft 30 and projects into the compartment 27 of the tank. A second drum 32 is also secured on the shaft 30 and projects into the compartment 28 of the tank. A gear 33 is secured on the free end of the shaft 30 at the rear side of the machine and meshes with a pinion 34 carried by a stub shaft 35 which is rotatably mounted in a bearing housing 36 carried by the frame B. A sprocket 37 is secured on the stub shaft 36 and is driven by a chain 38 from a motor 39 as best shown in Figure 3. The drums 31 and 32 are thus positively driven.

The compartment 27 of the tank 25 is supplied with metal cleaning solution such as caustic alkali through a feed pipe 40. The feed can be controlled with a valve 41 in the feed pipe 40 and solution can be drained from the compartment 27 by removing a drain plug 42 at the bottom of the tank.

The compartment 28 of the tank 30 is supplied with lime water through a feed pipe 43 and the feed is controlled by a valve 44. Obviously lime could be directly introduced into the compartment 28 and water could be supplied through the inlet pipe 43. The lime water can be removed from the compartment 28 by removal of a drain plug 45 in the bottom of the tank.

The rod R from the guide 24 is directed around the drum 31 for a plurality of turns such as, for example, ten or twelve turns. Since the drum is positively driven from the motor 39 it will pull the rod through the descaling sheave assembly and immerse the rod in the caustic alkali solu-

tion in the compartment 27. A plurality of immersions will be effected since, as shown, the top portion of the drum is above the tank 25.

After passing around the drum 31 for the desired number of turns, the rod is directed upwardly over a sheave 46 supported on a shaft 47 extending longitudinally of the machine. The rod then passes downwardly from the sheave 46 and around the second drum 32 for a plurality of turns. The drum 32 is driven with the drum 31 from the motor 39 and carries paddles 32a around the periphery thereof to agitate the lime in the compartment 28. The rod on the drum 32 is thus immersed for a plurality of times in the lime water.

In accordance with this invention the rod, after passing around the drum 32 for several turns, is directed upwardly from the drum over sheaves 48 and 49 mounted on shafts 50 and 51 respectively, above the shaft 47 and extending at right angles to the shaft 47 or transversely across the width of the machine. The rod thus passes upwardly from the drum 32 above the sheave 46 and over the sheaves 48 and 49. The rod is then directed downwardly through an open ended vertical tube 52, passes through this tube, and is guided by another sheave 53 back onto the drum 32.

The interior of the tube 52 is heated by an electric resistance element 54. In this manner the rod is coated with lime as it passes on the drum 32 into and out of the lime bath in the compartment 28. The coating on the rod is then dried as the rod passes through the tube 52. The dried and coated rod is again passed around the drum 32 and re-immersed in the lime bath to receive an additional coating thereon. After passage around the drum for several more turns, the rod is directed off of the drum over a sheave 55 rotatably carried by a bracket 56 secured on the horizontal plate 11 as best shown in Figure 3. The rod then passes upwardly to a sheave 57 rotatably mounted on a shaft 58 extending across the width of the machine above the descaling assembly as shown in Figure 1. The sheave 57 is positioned at a higher level than the sheaves 48 and 49 so that the rod can pass horizontally above those sheaves and thence over another sheave 59 and again into the heated tube 52 where the second coating thereon is dried.

After the second passage through the tube 52 the rod is directed under a sheave 60 rotatably carried from the framework B. A drawing die box 61 next receives the rod. This box 61 carries a replaceable reducing die 62 for drawing the rod down to wire size. As best shown in Figure 3, a wire drawing drum 63 pulls the drawn wire through the die 62. This drum receives the drawn wire for a plurality of turns therearound and is driven from the same motor 39 that drives the drums 31 and 32. A portion 61a of the die box 61 ahead of the die 62 can be filled with drawing die lubricant such as soap compositions or the like and the rod R passes through this lubricant en route to the die 62.

The heavy lime coating on the rod not only serves to protect the rod against oxidation but also serves as a lubricant-retaining medium to pick up and retain lubricant from the die box portion 61a. This greatly facilitates the drawing operation.

Since the drums 31 and 32 are driven in timed relation with the wire drawing drum 63, the rod entering the drawing die 62 is not under tension. As a result, breakage is materially decreased and

improved metallurgical properties can be developed.

In the embodiment shown in Figures 4 and 5, parts identical with parts described in Figures 1 to 3 have been marked with the same reference numerals.

In Figures 4 and 5 the rod R is directed from the drum 31 over the sheave 46 and around the drum 32 for several turns. The rod is then led off of the drum 32 and over the first set of pulleys 48 and 49 for passage through the heating tube 52. The rod is again wrapped around the drum 32 for several turns and is again directed over an additional set of pulleys 48 and 49 on the same shafts as the first mentioned pulleys and again passes through the heating tube.

After the second passage through the heating tube the rod is wrapped around the drum 32 for several more turns and is then directed over the pulleys 57 and 59 for a third passage through the tube 52. The rod is then directed under the sheave 60 in the same manner as shown in Figures 1 to 3.

In this modification, therefore, the rod is subjected to three drying operations and is re-immersed after the first two drying operations.

In Figure 6 there is illustrated a modified drying tunnel 70 of rectangular shape. This drying tunnel receives four passes of the rod R therethrough and is heated by electric grid 71 which bridges the center of the tunnel.

It should be understood that any type of drier can be used, and that the rod can be subjected to as many drying operations as desired.

This invention therefore now provides an improved descaling, cleaning and lime coating apparatus utilizing driven drums for propelling elongated metal material through a mechanical descaler and through chemical treating baths for feeding a cleaned limed material into a fabricating machine in an unstressed condition. A lime coating can be built up with any desired thickness by regulating the number of drying operations and immersions. Only a single lime tank need be used for the multi-lime coating. This tank is preferably heated and may be equipped with any suitable type of heating coils or supplied with live steam.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a lime coating device for elongated metal material including a tank for holding a bath of lime water, and a drum rotatably mounted in said tank for receiving a plurality of turns of elongated metal material therearound to immerse the material in the lime bath, the improvements which comprise guide sheaves receiving and guiding the elongated material from and back to said drum to produce an elongated run of the material, a heating tunnel surrounding said elongated run in spaced relation therefrom, other guide sheaves for receiving and guiding the material away from said drums, a drawing die for receiving the material from said last guide sheaves, a drawing drum for receiving the material from said die, and means for driving said drawing drum and said tank mounted drum in timed relation whereby the metal material is lime coated and dried and is fed by the tank mounted

drum to the drawing die in a condition free from axial tension.

2. A lime coating device for elongated material comprising a tank having separated compartments for holding liquid baths including a lime bath, a rotatable drum partially submerged in each bath for receiving a plurality of coils of elongated material therearound, means for transferring said material from one drum to the other, guide sheaves defining elongated runs for said material, one of said runs guiding the material away from and back to said drum in the lime bath and the other elongated run guiding the material away from said drum, a drier in the path of one of said runs, a drawing drum for receiving said material through said other elongated run from the drum in said lime bath, and means for driving said drawing drum and the drum in said lime bath in timed relation for feeding the material from the lime bath drum to the drawing drum in a condition free from axial tension.

3. In a mechanical descaler and wire drawing assembly including descaling sheaves for flexing wire to crack off scale therefrom together with a drawing die, the improvement which comprises a lime coating apparatus between the descaler and drawing die having a drum receiving therearound a plurality of turns of the wire from the descaler, a tank receiving the drum therein and adapted to hold a lime bath for lime coating the wire on the drum, and means driving said drum to pull the wire through the descaler and the lime bath and for feeding the descaled limed wire to the drawing die in a condition substantially free from axial tension.

4. In a mechanical descaler and wire drawing assembly including descaling sheaves for flexing wire to crack off scale therefrom together with a drawing die, the improvement which comprises a lime coating apparatus between the descaler and drawing die having a tank with separated compartments therein for holding liquid baths including a lime bath, a rotatable drum partially submerged in each bath for receiving a plurality of coils of the wire therearound, means for transferring said wire from one drum to the other, guide sheaves defining elongated runs for said wire, one of said runs guiding the wire away from and back to said drum in the lime bath and the other elongated run guiding the wire away from said drum, and means driving said drums in said baths to pull the wire through the descaler and the lime bath and for feeding the descaled limed wire to the drawing die in a condition substantially free from axial tension.

5. In a mechanical descaler and elongated metal material fabricating assembly including descaling sheaves for flexing elongated metal material to crack off scale therefrom together with a fabricating apparatus for acting on elongated metal material, the improvement which comprises a lime coating device between the descaler and fabricating apparatus, said device having a drum receiving therearound a plurality of turns of the elongated metal material from the descaler, a tank receiving the drum therein and adapted to hold a lime bath for lime coating the elongated metal material on the drum, and means driving the drum to pull the elongated metal material through the descaler and the lime coating bath for feeding the descaled limed elongated metal material to the fabricating apparatus in a condition substantially free from axial tension.
